RESISTOR CONNECTER DEVICE

John M. Bowman, Philadelphia, Pa., assignor to
 Philadelphia Storage Battery Company, Philadelphia, Pa., a corporation of Pennsylvania

Application January 13, 1932, Serial No. 586,396

3 Claims. (Cl. 201—63)

This invention relates to electrical connector devices and has particular reference to devices for electrically and mechanically connecting a conductor to an electrical element. While its application is general, the invention is specific to suppressor resistor elements utilized in connection with motor vehicles equipped with radio receivers. The principal object of the invention is to provide a simple and efficient connector device 10 which is particularly adapted for its intended purpose.

Other objects as well as the specific features of the invention will be clearly understood from the following detailed description and the accompanying drawing in which:

Fig. 1 is a schematic illustration of the device as it is intended to utilize the same; and

Fig. 2 is a sectional view clearly illustrating the device.

Without limiting its applicability, the invention is illustrated herein as applied to the specific device for which it is intended, as indicated above. For the purpose of the present description, it suffices to state that suppressor resistor elements are interposed in the spark plug lead or supply conductor of a motor vehicle equipped with a radio receiver, the purpose of the resistor being to prevent disturbances originating in the ignition system of the vehicle from interfering with the normal operation of the radio receiver. Fig. 1 illustrates this arrangement clearly, wherein 1 designates the usual cylinder head of a motor vehicle. 2 designates a spark plug thereof. 3 and 4 are sections of the spark plug conductor, 35 and 5 is the suppressor resistor element with the novel device of the invention applied thereto.

Referring to Fig. 2, wherein the invention is illustrated in detail and the elements of Fig. 1 have been given like reference characters, the suppressor resistor is shown at 6 and takes the usual cylindrical form of such elements. In accordance with the invention, the simple and efficient mechanical and electrical connection of conductor sections 3 and 4 is made to the ends or terminals of element 6. To this end, a pointed screw 7 having sharp threads is attached to each end of the resistor element. Preferably, the screw resembles an ordinary wood screw, and a cup-shaped retainer 8, which is preferably of brass, serves to retain the screw by engaging the flanged head 9 thereof. The shank of the screw extends through the apertured opening 10 in the bottom of retainer 8. The retainer is of such dimension that the end of the resistor element 55 fits nicely therein. Preferably, a layer of steel

wool 11 is interposed between the head of the screw and the resistor element. A binding of cement 12 or like substance serves to attach retainer 8 to the resistor element securely. It will be understood that both ends of the device are 5 formed as described.

As illustrated clearly in Fig. 2, the usual insulated stranded conductor used for spark plug conductors and other purposes may be readily connected to the device by merely screwing the 10 threaded shank of screw 7 into the end of the stranded conductor longitudinally thereof. The individual strands of the conductor interlock firmly with the screw threads to provide a very 15 efficient mechanical and electrical connection.

If desired a protective sleeve 13 of any suitable insulating material, such as porcelain, may be applied to the device so as to closely encircle the resistor and to completely cover the connecting joints. No claim is made to this protective sleeve 20 in this application excepting in combination with the particular connector, since the sleeve per se forms the subject matter of a co-pending application of Anton A. Leonard, Serial No. 586,389, filed Jan. 13, 1932. If the sleeve is used, it may 25 be so applied as to be firmly held in place by the cement 12 and used to hold the elements of the device together. It is further to be noted that screw 7 expands the conductor and its insulation, thus jamming or wedging the insulated conductor 30 in the sleeve. This enhances the efficiency of the device from the standpoint of electrical connection and mechanical security.

Obviously, various changes and modifications in the specific construction of the device may be 35 made without departing from the spirit and scope of the invention. Only such limitations as are contained in the appended claims, therefore, are to limit the invention.

I claim:

1. A resistance device comprising a tube or sleeve of insulating material, an electrical resistance element within said tube, a screw within an end of said tube extending axially from an end of said resistance element, said screw having 45 a flanged head adjacent the said end of said element, a retainer member securely engaging said screw head, and means securing said retainer member within said tube to hold the said screw within the tube end in electrical association with 50 the end of said resistance element, said screw being adapted to be forced into the core of an insulated conductor inserted in the end of said tube to simultaneously electrically connect said resistance element with the conductor core and ex- 55

pand the end portion of the conductor insulation against the inner wall of the tube.

2. A resistance device comprising a housing of insulating material having a bore, an electrical resistance element within said bore, a screw within each end of said housing extending axially from an end of said resistance element, each said screw having a flanged head adjacent the associated end of said resistance element, a cup-shaped retainer member fitted over each end of the resistance element and having an annular flange securably engaging the associated screw head, and means securing the retainer members within said housing to hold said resistance element therein and to hold the screws within the housing ends in attachment with the ends of the resistance element, each said screw being adapted to be forced into the core of an insulated conductor to simultaneously electrically connect said resistance element with the conductor core and wedge the end portion of the conductor insulation into intimate contact with the cylindrical wall of the housing.

3. The combination with a suppressor resistor element for connection in the ignition circuit of a motor vehicle equipped with a radio receiver, of means for electrically and mechanically connecting an insulated conductor to said resistor element, comprising a pointed screw extending axially from an end of said resistor element and having a flanged head adjacent the said end, a retainer member fitted over the said end of said resistor element and having an annular flange securably engaging said screw head, an annular element surrounding the said end of said resistor element and extending along the shank of the screw, and means securing said retainer member and said annular element to the resistor element, whereby there is provided adjacent the said end of the resistor element, a well in which the screw shank is seated and into which the said conductor may be inserted, with the screw shank engaging the conductor core and expanding the end portion of the conductor insulation against the inner wall of said well.

JOHN M. BOWMAN.
